FOREIGN PATENT DOCUMENTS

DE 3734003 5/1988

* cited by examiner

Primary Examiner—Louis Zarfas*Assistant Examiner*—Michael A. Pratt*(74) Attorney, Agent, or Firm*—Banner & Witcoff, Ltd.(57) **CLAIM**

The ornamental design for a portion of a wrist band, as shown and described.

DESCRIPTION

FIG. 1 is a perspective view of a portion of a wrist band showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the generally trapezoidal shaped regions on the sides and the remainder of the wrist band in FIGS. 1-7 is for illustrative purposes only and forms no part of the claimed design.
